(57) **CLAIM**

The ornamental design for a black and white cat shaped child's trolley toy, as shown and described.

DESCRIPTION

FIG. 1 is a side elevational view of the design

FIG. 2 is a rear lateral view of the design

FIG. 3 is a front lateral view of the design; and,

FIG. 4 is a plan side view of the design.

The broken line showing is for illustrative purposes only and forms no part of the claimed design.

The design disclosed and claimed herein, and illustrated in the above-described figures, is not intended to include the leash depicted in said figures.
